UNITED STATES PATENT OFFICE.

CLIFTON F. LEATHERBEE, OF NEWTON, MASSACHUSETTS, ASSIGNOR TO PAINTING MACHINE COMPANY, OF KITTERY, MAINE, A CORPORATION OF MAINE.

COATING APPARATUS.

1,209,177.

Specification of Letters Patent. Patented Dec. 19, 1916.

Original application filed April 4, 1910, Serial No. 553,330. Divided and this application filed August 17, 1910. Serial No. 577,626.

To all whom it may concern:

Be it known that I, CLIFTON F. LEATHERBEE, a citizen of the United States, residing at Newton, in the county of Middlesex and 5 State of Massachusetts, have invented certain new and useful Improvements in Coating Apparatus, of which the following is a specification.

The present invention relates to machines 10 for applying liquids and fluids of various kinds to the surfaces of materials of various contours, and more especially to the provision of an improved form of apparatus which may be used to subject lengths of 15 flooring, strips of molding, cross arms, and like strips or lengths of moving material to the application of paint, stain, varnish, creosote and other finishing or preservative substances, to coat them with insulation, 20 and simultaneously to remove any excess of the applied substance and polish and finish the treated article.

The principal objects of my present invention are the provision of a machine characterized as above noted, which is adapted 25 to treat the material speedily and inexpensively and to apply the substance used with great facility and thoroughness to all the surfaces of material of irregular contour, 30 such as wainscoting, electric wiring conduits and the like; to provide feed regulating means whereby, when desirable, a minimum amount of the treating substance may be supplied to the applying means; to provide 35 means whereby any excess of material fed to the applying means may be removed from the machine and returned to the supply tank and used again to avoid loss, as well as certain further objects hereinafter more fully 40 to appear.

The present application is directed particularly to the features of the coating apparatus, the drying apparatus, the feeding mechanism, and the conveyer forming the 45 subject matter of my co-pending application Serial No. 553,330, of which the present application is a division, and of other divisions of said application namely Serial Nos. 577,626 and 577,625.

50 In the attainment of the objects above set forth, together with additional advantages to be disclosed below, I have provided a construction, a preferred embodiment of

which is illustrated in the accompanying drawings wherein—

Figure 1 is a side elevational view, partly in section, illustrating the feeding fluid applying and polishing mechanism; Fig. 2 is a plan view of the machine shown in Fig. 1; Fig. 3 is a sectional view taken on the line III—III of Fig. 2; Figs. 4 and 5 respectively are plan and sectional views of a modified detail of construction.

Referring now more particularly to Figs. 1 to 3, it will be noted that in carrying out 65 my invention I make use of a framing 20, preferably of cast metal provided at each end with supports 20', which may be conveniently located adjacent to the end of a planer or other machine for forming floor- 70 ing, wainscoting and similar products. Inasmuch as I find machines embodying my improvements peculiarly available in connection with the use of quick-drying fluids containing volatile oils, I prefer to have 75 them closed to the atmosphere in order to avoid the evaporation, using therefor a light cover for the top, (not shown). At the delivery end of the machine, I provide a primary belt conveyer 21 longitudinally disposed with relation thereto for removing the treated material discharged therefrom.

In order that the increase of cost and loss of time incident to rehandling the material after leaving the planer, may be saved and 85 to insure a direct feed of such material through the machine without lateral displacement, it may be fed by the live rolls of the planer; otherwise such feed may be effected by the oppositely disposed live rolls 90 23 and 24 driven from the motor 25 through the gearing to be hereinafter described. A stationary guide block 26 and a spring guide 27 disposed oppositely thereto and co-operating therewith are located closely adjacent 95 the rolls 23 and 24 to insure the alinement of the material as it is fed through the machine. A roll 28 is provided for the initial support of the fed material, and as it passes the rolls 23 and 24 it is successively engaged by the 100 single idler roll 30, and the pairs of live rolls 31, 32, and 33, 34 adapted to hold it in contact with the brush devices 35, 36, 37 and 38, designed respectively for applying the liquid, for rubbing it in, for wiping any 105 excess from the edges of the materials and

for removing any vestiges from the face thereof.

On viewing Fig. 1 particularly it will be observed that I mount in the framing 20 the 5 rotatable brush 35, movable vertically to the end that compensation may be made for wear in service by means of its suspension in the outer ends of the yoke 40 whose shaft is pivoted in the casing as indicated at 41, 41, 10 one of said ends being provided with an adjusting screw 42.

For the purpose of furnishing a supply of treating liquid to the brush 35, I make use of a pump 45 to lift the liquid from the sup- 15 ply tank 46 by the pipes 47 and 48 leading from such tank and venting just above the spreader plate 50 pivoted at 51 to a trans- 20 verse septum 52 in the framing and held in contact with the brush 35 by means of an adjusting screw 53 threaded into an enlarged portion of the framing at the angle 54, whereby wear of the brush may be further compensated for. The floor 55 of the framing forms a drip pan for the several brushes 25 and a drain pipe 56 continuously open to the tank 46 is provided to convey thereto any excess liquid that may perchance fall upon such pan.

For driving the pump 45, the brush 35, 30 and the rolls 24, 32 and 34, in unison, to the end that a uniform application of liquid may be had, I mount on the shaft of the motor 25 a pulley 60 driving by means of a belt 61 the pulley wheel 62 which is mounted 35 on the shaft 63 carrying the roll 34. The opposite end of the shaft 63 is provided with a gear 65 which by means of a chain 66 drives the gear 67 mounted on the shaft 68 of the roll 32. The shaft 68 carries on the 40 end, (opposite to that carrying the gears 67 and 69), a gear 73 driving, by means of the intermediate gears 74 on a shaft 74^a, and 75 on the shaft 76, the gear 75^a on the shaft 76^a carrying the roll 31. At the end of said 45 shaft 76 is mounted a sprocket wheel 77 driving by means of the chain 78 the pump 45. On the end of the shaft 72 opposite the sprocket 71 is carried a gear 79 which through intermediate gears 80 on the shaft 50 80^a, and 81 on the shaft 82 drives the gear 82^a on the shaft 83^a carrying the roll 23. Upon said shaft 82 is mounted a pinion 83 driving through the chain 84 the sprocket 85 on the shaft 86 carrying the brush 35.

55 In order that the upper rolls 23, 30, 31 and 33 may be adjusted axially to accommodate materials of differing thicknesses, and that they may be conveniently removed where desirable, I preferably mount them in 60 the opposing members of pairs of boxes 88, 89, 90 and 91 pivoted to opposite sides of the framing 20, each box being provided at its free end with an adjustable screw device 92 having engagement with an extension of 65 the box and inserted and having threaded

engagement in a socket formed in the framing. Springs 92^a—92^a under a certain degree of compression are mounted upon the said screw device 92 on both sides of said extension in order to compensate for any slight unevennesses in the material.

Inasmuch as I have designed the machine illustrated as an embodiment of my present invention primarily for the purpose of employing a highly volatile treating compound 75 to flooring, the respective sizes of the pulley 77 and 77' by which the pump is driven through the belt 78, should be so proportioned that as closely as possible the precise amount of liquid that may be taken up by 80 the brush 35 be delivered upon the spreader plate 50, in order to avoid any accumulation upon the drip pan 55 or the rolls. As a further precaution against spattering of the liquid, or throwing thereof from the brush 85 35, I provide such brush with a cover 35^a, open at the top, and supported by the shaft 86 and yoke 40. This is especially desirable since my improved machine is used with great economy for the treatment of flooring 90 as it issues from the planer, and such locations usually present a considerable amount of dust, chips, shavings and other highly inflammable substances.

To insure that the liquid as it is ejected 95 from the pipe 48 is distributed evenly over the spreader plate 50, I mount on the open end of the pipe a striking plate 48^a which also serves the further purpose of preventing any spattering of the fluid on the brush 100 35 or the framing 20 and thus prevents accumulation thereon of the heavier residue held in suspension in the volatile fluid of such paint. As a further guard against accumulation of residual material, I provide 105 the rolls 30, 31 and 33 with shields 30^a, 31^a and 33^a.

Each of the stationary brush devices 36 and 38 is vertically adjustable by means respectively of the screw devices 95, 96 threaded 110 into a bottom extension of the framing 20, to the end that compensation may be had for any wear of such brushes in service, and each of the brushes 36, 37 is adjustable laterally by the screw members 97, 97 threaded 115 into the sides of the framing 20 and resting at their inner ends in the stop blocks 98, carried upon a plate 99^a supported by the angle bars 99, 99, also mounted in the framing 20, for the purpose of limiting the inward movement of the said brushes 37.

For a three-fold purpose, viz., alining the material in its passage through the machine, directing it between the two brushes 37, and holding it in contact with the brush 125 36 (here shown as made in three parts carried in a frame 36^a for the sake of convenience in replacement and in order that unequal wear of the several parts may be cared for without discarding unworn por- 130

tions), I provide the coöperating spring devices comprising the laterally pressing, oppositely disposed springs 100, 100 adjustably mounted in blocks 101, 101 carried by the yoke 102, and the downwardly pressing spring 103 in the block 104, provided upon said yoke 102 between the springs 100.

Referring now to the alternate arrangement illustrated in Figs. 4 and 5, it will be observed that in this construction, in lieu of the stationary brush 38, I make use of a revolving brush 38^a mounted in bearings 105, 105 carried by the arms 106, 106 of the yoke 107 pivoted in the framing 20 as indicated at 108, 108 and adjustable vertically by the screws 109 threaded into the framing as indicated at 110' at each side thereof, sustaining such bearings. The brush 38^a is driven from the shaft 63 by means of a pinion 105^a connected to the sprocket 106^a on the shaft 107^a carrying such brush, by a chain 108^a. In the present device, as in that of Figs. 1 to 3, the roll 33 is driven by means of the gears 111' carried on the shaft 63, the intermediate gears 112' and 113' on shafts 112^a and 113^a, and the gear 114' mounted on the shaft 115' of said roll 33. In the device of Figs. 4 and 5 the roll 34 serves not only as part of the means for sustaining and feeding the material through the machine, but also for the purpose of removing from the brush 38^a any liquid that may have accumulated thereon ensuing upon the progress of material through the machine, and over such brush, whereas in the device of Figs. 1 to 3, the roll 34 serves the sole purpose of sustaining and feeding such material.

Having thus described my invention and illustrated its use, what I claim as new and desire to secure by Letters Patent is the following:

1. In a machine for treating material, in combination, means adapted to receive moving material, means for applying liquid to the material, and upwardly and downwardly movable means yieldingly resstantly held against both upward and downward movement for holding the moving material in contact with the applying means.

2. In a machine for treating material, in combination, means adapted to receive moving material, means for applying liquid to the material, means for rubbing in the liquid and removing excess thereof from the material, and resilient means acting on the moving material for holding it in contact with the removing means.

3. In a machine for treating material, in combination means adapted to receive material, a source of liquid supply below said means, a stationary spreader for the liquid below said source of supply, means for distributing liquid flowing from said source of supply along the upper portion of said spreader and means adapted to take up liq-

uid from the spreader and apply it to the under side of the moving material.

4. In a machine for treating material, in combination, means adapted to receive moving material, a source of liquid supply below said means, a stationary inclined spreader for the liquid, a moving brush having a periphery in continuous contact with the spreader adapted to take up liquid from the spreader and apply it to the under side of the moving material, and a second brush for rubbing in the liquid and removing any excess thereof.

5. In a machine for treating material, in combination, means adapted to receive moving material, a source of liquid supply below said means, a stationary inclined spreader for the liquid, a moving brush having a periphery in continuous contact with the spreader adapted to take up liquid from the spreader and apply it to the under side of the moving material, and an auxiliary brush disposed at an angle to the first brush for rubbing in the liquid and removing any excess thereof.

6. In a machine for treating material, in combination, means adapted to receive material, a source of liquid supply, a spreader for the liquid, a moving brush adapted to take up liquid from the spreader, and means for directing the liquid as it comes from the source of supply away from the brush and onto the spreader.

7. In a machine for treating material, in combination, a source of liquid supply, a spreader, means for taking up liquid from the spreader and applying it to moving material, means above said spreader for supplying liquid from said source of supply to said spreader, and means for returning any excess liquid from the spreader to said source of supply.

8. In a machine for treating material, in combination, means adapted to receive material, a container provided with a source of liquid supply, a brush rotatably mounted in said container, a spreader plate for supplying liquid to said brush from said source of supply, and means for varying the relation of said spreader plate to the axis of said brush.

9. In a machine for treating material, in combination, means adapted to receive moving material, a container provided with a source of liquid supply, a brush rotatably mounted in said container, a spreader plate for supplying liquid to said brush from said source of supply, and means for moving the axes of said brush and spreader relatively to the plane of traverse of said moving material.

10. In a machine for treating material in combination means adapted to receive moving material, a rotary brush, a member parallel to the axis of said brush, arms

rigidly attached to said member and spaced apart the length of the brush, bearings for said brush attached to said arms, bearings for pivotally supporting said member and a screw device acting on the free ends of one of said arms whereby the position of said member and the brush carried thereby relatively to the bearings of such member may be adjusted.

10 11. In a machine for treating material, in combination, means adapted to receive moving material, a brush mounted for movement relatively to said material, a spreader plate for furnishing liquid to said brush, a roll for feeding material to said brush, a pump for supplying a positively controlled supply of liquid to the spreader, and means for driving said brush, roll and said pump at a substantially uniform rate of speed 20 relative to each other.

12. In a machine for treating material, in combination, a source of liquid supply, a moving brush for applying liquid to material, a spreader plate between said brush and source of supply, a brush for rubbing said liquid into material moving through the machine, and a brush disposed at an angle to said second brush for removing any excess liquid from said material, and means 30 for returning said excess liquid to said source of liquid supply, all so arranged that the moving material receives an application of liquid as it passes said first mentioned brush and any excess thereof is removed 25 therefrom as it passes said last mentioned brush.

13. In a machine for treating material, in combination, means for imparting movement to the material, means for applying liquid

to one plane of the material, and means for 40 removing liquid from the edges of said material, movable in a plane at an angle to that of said applying means and means for returning said excess liquid to said source of liquid supply. 45

14. In a machine for treating material, means for imparting movement to the material, means for applying liquid to one plane of the material, and means for removing liquid from the edges of said material 50 movable in a plane at an angle to that of said supplying means, and means for directing the material against said removing means.

15. In a machine for treating material, in 55 combination, a source of liquid supply, a brush for applying liquid from said source of supply to moving material, a spreader, a deflector for directing the liquid away from said brush on to the spreader, and means 60 for imparting motion to said brush.

16. In a machine for applying liquid to moving material, a casing a roll in the casing for moving material through the casing, a source of liquid supply, means for applying liquid from said source of supply to the moving material, a spreader, and a deflector between said applying means and said roll 65 for preventing the approach of liquid from said applying means to said roll and onto 70 the spreader.

In testimony whereof I have hereunto signed my name in the presence of the two subscribed witnesses.

CLIFTON F. LEATHERBEE.
